FLOORING

Frank A. Grunert, Menlo Park, Calif.

Application September 29, 1937, Serial No. 166,335

5 Claims. (Cl. 20—8)

This invention relates to flooring and particularly to flooring used for so called parquet floors, or hard wood floors.

A parquet-floor or the usual hard wood floor is usually made of blocks laid side by side. Each block is in turn made of several pieces of flooring such as hard wood slats interlocked to form a pattern in the block.

An object of the invention is to provide flooring pieces which can be interlocked into blocks in such a manner as to provide on the edges of the blocks longitudinal grooves so arranged as to facilitate the squaring up and the locking of the blocks in place by the use of suitable separate locking means such as keys.

Another object of the invention is to provide flooring blocks which are easily aligned, slid in place, and interlocked by a key, so as to form a solid smooth flooring.

Another object of this invention is to provide a flooring which is highly useful and simple in construction. Convenience of arrangement, lightness and comparative inexpensive of manufacture are further objects which have been borne in mind in the production and development of the invention.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawing.

With the foregoing and other objects in view, which will be made manifest in the following detailed description and specifically pointed out in the appended claims, reference is had to the accompanying drawing for the illustrative embodiment of the invention, wherein:

Figure 1 is a fragmental plan view of a floor, showing flooring in place constructed in accordance with my invention.

Figure 2 is a sectional view of my flooring the section being taken on the line 2—2 of Figure 1.

Figure 3 is a plan view of my flooring piece.

Figure 4 is an edge view of my flooring piece.

Figure 5 is an end view of my flooring piece.

Figure 6 is a fragmental, perspective view of my flooring piece.

Figure 7 is a perspective detail view of the key used in my flooring, and

Figure 8 is a fragmental sectional view showing the joining of my flooring pieces.

In its general organization my flooring includes blocks 15, preferably of polygonal, such as rectangular, outline as shown in Fig. 1. Each block has a tongue 16 extended from one edge, grooves 17 and 18 on the edges at right angles to the tongue 16, and a groove 19 on the edge 10 parallel with the tongue 16.

These blocks 15 are so grouped together that two pairs of the meeting edges of the blocks are grooved edges and into the aligned grooves at such meeting edges is inserted a key 21.

An end of the key 21 projects at 22 beyond the corner of the blocks so as to extend into grooves at the meeting corners or points of two other blocks thereby squaring up the meeting points of the four blocks.

In detail my invention includes flooring elements, or pieces 23 joined side by side so as to form one of said blocks 15. Each piece 23 is made substantially as illustrated in Figures 3 to 6 inclusive. The flooring piece 23 is an elongated rectangular piece preferably made of suitable hard wood. On one longitudinal edge the flooring piece 23 has a longitudinal tongue 16. In the other longitudinal edge of the flooring piece 23 is provided a groove 19. In the opposite ends of the flooring piece 23 are provided the grooves 17 and 18.

All the grooves and tongues are intermediate on the respective edges between the top and bottom of the piece 23. Each groove is of a cross sectional shape of half a dovetail the wider parallel side, or base of which forms the bottom 26, of the groove, while the shorter parallel side or top of the half dovetail forms the slot 27 of said groove. It is preferable that the side 28 at right angles to the base 26 form the upper side of the groove and the inclined side 29 be the lower boundary of said groove. The tongue 16 is of a cross sectional shape to fit exactly into said grooves. The tongue 16 is cut away at both ends 40 and in the cut away places are formed short grooves at 22 of the same shape as of the other grooves heretofore described. In other words all the grooves and tongues on the flooring piece 23 are of the same cross sectional contour, namely 50 of a shape that may be described as that of a symmetrical half of an isosceles trapezoid, the base of which forms the bottom 27 of the grooves or the corresponding top side of the tongue. It is to be noted that the tongue 16 may be made 55

removable by grooving that side of the flooring piece 23 throughout its length and by making the tongue 16 separately in the shape of the key 21 and slide it in place at will.

5 The key 21 is made of a cross section to exactly fit a pair of aligned grooves. Therefore the cross sectional shape of the key 21 may be described as two symmetrical half dovetails joined at their narrower parallel sides. In other words two. 10 half isosceles trapezoids united so that the bases are the outside walls 31 of the key 21 while the shorter parallel tops coincide as the center line of the key 21 and the right-angle sides are contiguous to form the top plane 32 of the key 21. 15 18 Each key 21 is longer than the longitudinal side of a piece 23.

In operation the flooring pieces 23 are first interlocked by sliding the tongues 16 of one into the corresponding groove 19 of the next flooring piece. After several pieces 23 are so interlocked they form a flooring block 15 heretofore described. One tongue 16 remains protruding from a side of the block 15, while in the opposite parallel edge of the block remains an empty groove 19. The grooves 17 and 18 in the ends of the flooring pieces 23 are in registry to form continuous grooves in the right angle edges of the blocks 15 as heretofore described.

Then the finished blocks 15 are laid, for instance in the manner shown in Fig. 1. The first block 15a has its tongue 16 pointing toward the next block 15b which latter is slid over said tongue 16 by its end groove 18. The tongue 16 of block 15b points at right angles to the tongue of the first block 15a and is engaged by the end groove 17 of the third block 15c. Such arrangement causes the tongue 16 of the third block 15c to be in staggered parallel position relatively to the tongue 16 of the first block 15a. The fourth meeting block 15d is so placed that its tongue 16 is in staggered parallel position relatively to the tongue 16 of the second block 15b. Where grooved edge meets grooved edge, as the end groove 18 of the first block 15a and the side or longitudinal groove 19 of the fourth block 15d or the groove 19 of the third block 15c and the end groove 17 of the fourth block 15d, the blocks are bound together by inserting keys 21. Therefore the order of laying the blocks would be as follows: first the first block 15a is put in place, then the fourth block 15d is placed alongside and a key 21 is inserted endwise into the aligned grooves 18 and 19. Then the second block 15b is slid in place over the tongue 16 of the first block 15a. Then the third block 15c is slid over the tongue 16 of the second block 15b, and lastly a key 21 is inserted into the aligned grooves 19 and 17 of the respective blocks 15c and 15d. The last mentioned key 21 projects into the cut away corners of the first and second blocks 15a and 15b thereby squaring up the meeting points of the four blocks into one firm unit. The other end of each key 21 is spaced from the ends of the corresponding grooves to a distance equal the depth of a groove or one half of the width of the next key 21. This operation can be continued repeatedly throughout the floor providing a staggered step-like arrangement of positioning keys 21, which all overlap in one direction only into the corners of adjoining blocks. The flooring blocks may be

keyed together separately into selected size larger floor sections even before laying if so desired.

Having thus described my invention what I now claim and desire to secure by Letters Patent is:

1. A flooring of the character described comprising a plurality of polygonal blocks positioned side by side so that their meeting edges abut against each other and form a corner, certain of said meeting edges having longitudinal retaining grooves in registering position, and a key so shaped as to interlock with both of said registering grooves to bind the edges together, said key protruding into said corner so as to square up the meeting points of said adjoining blocks, other meeting edges of said adjoining blocks being joined together by tongues and groove joints.

2. A flooring comprising a plurality of substantially rectangular blocks, each block having longitudinal grooves on three edges, a longitudinal tongue on the fourth edge of each block, said blocks being so positioned that the meeting edges of the blocks on two adjacent sides are both grooved, but on the other two adjacent sides the tongue of one block is engaged with the opposed groove of the other, and a key in each pair of opposed grooves to hold the blocks together, a recess formed in the end of each edge having a tongue, said keys extending at one end into said recess and into the groove opposite said recess so as to align the meeting points of the adjoining blocks.

3. A flooring made of a plurality of blocks, each block being made of a plurality of parallel pieces interlocked by tongue and groove joints on the longitudinal edges thereof, said pieces also having aligned grooves in each end thereof, said blocks being so arranged that two adjacent sides of adjacent blocks are also interlocked by tongue and groove joints, and the remaining two adjacent sides of the respective blocks have their grooves aligned, and a key inserted into each pair of such aligned grooves, the tongues being cut away at the ends thereof and a short groove being formed at said cut away portion, and said key overlapping into said short grooves so as to square up the meeting points of the adjoining block.

4. In a combination a flooring element having a tongue and groove respectively on the opposite longitudinal edges thereof, and having a groove in each end thereof, the ends of the tongue being cut away, and a key fitting into grooves on the meeting edges of adjoining elements, similar short grooves formed in place of the cut away ends of said tongue, the ends of said key overlapping into the respective short grooves.

5. In a flooring of the character described, a plurality of blocks for forming the flooring, said blocks having registering grooves in the meeting edges thereof, keys in said registering grooves, certain of said keys holding two adjacent blocks together and have an end extended into the corners of two other blocks in the meeting corners of said group of adjacent blocks, said keys extending in substantially parallel series at angles to each other so that each pair of consecutive keys engage two adjacent sides of the same block meeting at said corner.
